UNITED STATES PATENT OFFICE

KNUT SPERLING GÖRAN GYLLENKROOK, OF WAXHOLM, SWEDEN

SNOWPLOW

Application filed November 23, 1926, Serial No. 150,352, and in Sweden December 1, 1925.

In driving snow plows with the aid of tractors, which has been lately practised to great extent, the plow is generally connected to the tractor in front of the same, so that the tractor will shove the plow before it. The plow is then carried by carrying members sliding on the plowed plane, and the deep-drawing of the plow is controlled by the latter being raised or lowered relatively to the carrying member or members. The device which hitherto has been available for the purpose is not satisfactory. In the first place, the function of the carrying member sliding on the snow is obviously dependent on the nature of the snow. In loose, new-fallen snow the carrying member is apt to cut down into the snow, so that the plow, even if its elevated position relatively to the carrying member is adapted in a certain manner, still moves at too great a depth, often as far down as to the solid road. Hard-packed or wet snow evidently has a reverse action and actuates the carrying member upwards, so that the plow is brought into a position which is too elevated, the remaining layer of snow being then too deep.

This experience is responsible for the idea to provide such an arrangement of the carrying member proper that the same may be caused by a simple adjustment to carry to a greater or smaller extent.

To this end the invention in view is principally distinguished by the fact that different parts of the surface of the carrying member utilized for the carrying effect have a different extension in the carrying plane, the carrying member being adjustable in such a manner that a larger or smaller portion of the carrying surface will be active according as the carrying member is differently adjusted with respect to the nature of the snow.

The arrangement is devised in the simplest and most suitable manner so that the carrying member forming a downwardly arcuate sliding runner is made tapering toward the one end, preferably the fore end, which is pivotally attached to the plow in any suitable manner. Behind the pivot, the carrying member is movably connected to a device by means of which it may be swung vertically so that

the rear end of it is raised or lowered. On this adjustment, the width of the carrying surface is obviously increased or decreased according as the rear end is lowered or raised respectively.

55 The accompanying drawing illustrates an embodiment of the invention. Fig. 1 is a rear view of a snow plow provided with an arrangement according to the invention, and Fig. 2 shows the same viewed from the side in vertical section. Fig. 4 is a plan view of the carrying member, and Fig. 3 shows to an enlarged scale and in vertical section a mechanical device suitable for the adjustment of the carrying member.

60 Extending at the rear between the plow wings 1 is a shaft 2 with which the tractor therebehind is connected in such a manner that the plow may swing with its point up and down about the shaft. The shaft is carried at the ends by means of adjusting screws 3 which may be screwed up and down in nuts 4 rigidly connected with the plow wings 1. With the aid of ball and socket joints, the screws are connected with blocks 5 having the shaft threaded therein. This arrangement permits relative adjustment of the plow wings to the proper levels.

65 In the embodiment shown, the carrying member 6 according to the invention has the form of an isosceles triangle with a comparatively acute top angle with which latter the member is directed forwards and is pivotally attached to the plow near the point thereof, by means of a bolt 7 or in some other suitable manner. The carrying member is arcuate downwards and rearwards from the point of attachment, so that the carrying member is caused in any angular position to slide on the snow like a runner, without the risk being incurred of the carrying member cutting down into the snow or road. At the middle portion or approximately at the middle portion of the member 6, there is attached a sleeve 8 which is spherically shaped on the inside and which is adapted to enclose a ball 9 at the lower end of a screw 10, the threaded portion of which is engaged in a nut 11 provided at the front near the upper edge of the plow. The said nut 11 is spherical and enclosed by

two sockets 12 attached to the upper and lower sides of a plate 13 rigidly connected with the plow wings 1. Together with the sockets 12, the spherical nut 11 forms a ball and socket joint permitting the screw to be swung in the longitudinal central plane of the plow when screwed up or down, or when compelled to take part in any lateral movements of the carrying member 6. In order that the nut 11 shall not take part in the rotary movement of the screw, it is provided with a stud 14 entering a slot in the fixed parts 12, said slot having such an extension as to permit the said swinging movement of the screw in the central plane of the plow within the required limits.

When the screw 10 is screwed down, the carrying member is swung with its rear end downwards about the pivot 7 so that, according as the turning movement progresses, an ever increasing carrying surface of the member is made active. The looser the snow, the further will the carrying member be swung down. When the snow is wet or packed hard, the screw 10 on the contrary is screwed upwards so that the member 6 is raised at the rear end, whereby an ever decreasing surface of the member will be active, according as the screw is screwed further upwards.

Obviously, the details of the arrangement may be altered in the embodiment described and illustrated. As to the carrying member, the condition must be fulfilled, however, that it shall be of such a shape as to offer carrying surfaces of varying sizes in different positions of adjustment. It is also evident that more than one member arranged and acting in the manner set forth may be provided in the same plow.

What I claim as new and desire to secure by Letters Patent of U. S. A. is—

1. In combination with a snow plow having converging side members, of a carrying member of triangular shape in plan view and of a downwardly arcuate shape in longitudinal section, means for pivotally mounting said carrying member at its apex adjacent the intersection of said side members, means for adjusting said carrying member on its pivot relative to the side members; comprising a threaded ball joint held in spaced relation to said side members, and an adjusting screw passing through said ball joint, having its lower end articulated in said carrying member.

2. In combination with a snow plow having converging side members of a carrying member of triangular shape in plan view and of a downwardly arcuate shape in longitudinal section, means for pivotally mounting said carrying member at its apex adjacent the intersection of said side members, and means for adjusting said carrying member on its pivot relative to the side members comprising an adjusting screw articulated in said carry-

ing member at one end and connected through a ball joint fixedly mounted in spaced relation to said side members.

3. In combination with a snow plow having converging side members of a carrying member of triangular shape in plan view and of a downwardly arcuate shape in longitudinal section for making contact with the road along the curved surface of the member, means for pivotally mounting said carrying member at its apex adjacent the intersection of the side members, and means to adjust the carrying member on its pivot relative to the side members.

4. In combination with a snow plow having converging side members of a carrying member of triangular shape in plan view and of a downwardly arcuate shape in longitudinal section, means for pivotally mounting said carrying member at its apex adjacent the intersection of said side members, means for adjusting said carrying member on its pivot relative to the side members comprising a threaded ball joint held in spaced relation to said side members, an adjusting screw passing through said threaded ball joint having its lower end slidably engaging said carrying member, and a stud projecting from the spherical nut of the ball joint entering a slot in the fixed surrounding of the said ball joint thereby preventing the spherical nut from moving with the adjusting screw, the length of said slot being such as to permit of swinging of the adjusting screw within predetermined limits in the central plane of the plow.

In testimony whereof I affix my signature.
